CANDLE-SIMULATING FLUORESCENT LIGHTING FIXTURE

Filed Dec. 30, 1949

Inventor
Clifton E. Hays
by ~~Clark Knapp~~
His Attorney.

UNITED STATES PATENT OFFICE

2,598,054

CANDLE-SIMULATING FLUORESCENT
LIGHTING FIXTUREClifton E. Hays, Providence, R. I., assignor, by
mesne assignments, to General Electric Com-
pany, a corporation of New York

Application December 30, 1949; Serial No. 135,948

2 Claims. (Cl. 240—51.11)

1

My invention relates to ornamental or decorative electrical lighting fixtures, particularly those appropriate for the Christmas season. Specifically, the fixture of my invention is designed to produce the visual effect of an internally illuminated candle having a flame issuing from one end. Of course, this effect might be produced by a specially designed single lamp having the shape desired, but the manufacture of such a lamp would be expensive. Therefore, it is an object of my invention to produce a fixture which will obtain the desired visual effect by using standard forms or types of lamps which are readily available.

If the above effect is to be gained, this means that two separate lamps must be used, one for the cylindrical candle-simulating portion, and another for the flame-simulating portion. This immediately raises a problem in concealing necessary wiring, lamp sockets or electrical terminals and other electrical structures without destroying the desired illusion. Because the flame-simulating lamp is located at the far end of the cylindrical lamp away from the normal position for connection wires, there is a problem of getting these wires to the socket of the "flame" lamp without exposing them in an obvious manner. When a fluorescent lamp is used for the candle-simulating portion, as is preferred because of the even illumination obtainable from such a type of lamp, there is the additional problem of concealing the ballast and starter necessary for this lamp without sacrificing any of the decorative effect. My invention is designed to overcome all of these problems of concealing unattractive but necessary parts, and to produce an inexpensive fixture for obtaining the desired ornamental results.

The objects of my invention are met generally by providing a fixture having a base in which a lamp socket for the bottom of the cylindrical lamp is mounted, a supporting and wire concealing member extending upwardly from the base alongside this lamp and carrying a socket for the flame-simulating lamp, and a decorative covering for this socket and for the upper end of the cylindrical lamp.

Other objects and details of that which I believe to be novel and my invention will be clear from the following description and claims taken with the accompanying drawing, in which is an example of fixture according to my invention and incorporating a preferred form of support for the two lamps.

In the drawing, Fig. 1 is a side view of an ex-

2

emplary fixture with the lamps in place; Fig. 2 is a bottom view of the base of the fixture of Fig. 1; Fig. 3 is a vertical sectional view of the top of the fixture of Fig. 1 but on a larger scale; Fig. 4 is a plan view of the parts shown in Fig. 3, with portions broken away for clarity in illustration, and Fig. 5 is a wiring diagram for a preferred form of my invention.

Supporting the rest of the fixture, and housing the principal electrical parts is a base 1 made of any suitable material. This base is provided in its underside with a recess or cavity 2 in which various parts are supported and concealed in a manner to be later described.

15 In or on the top surface of this supporting base 1 provide an electrical socket 3 of a known type of construction for the lower end of a vertically extending cylindrical lamp 4 which will simulate an internally illuminated candle.

20 Offset rearwardly from the axis of the cylindrical lamp and extending vertically upward close to but parallel with the axis of the lamp 4, I provide a supporting member shown here as a wiring tube 5. This is made of rigid material 25 because it must support structures hereafter mentioned, and the lower end of the tube extends to and opens into the hollow portion 2 of the base. Naturally each fixture will be designed for a cylindrical lamp of a given diameter. The 30 lengths of these lamps are standardized so that the proper spacing between the lower lamp socket and the top of the wiring tube can be determined in advance. The tube is preferably, although not necessarily, made with a circular cross-section, with its greatest external diameter substantially less than the diameter of the cylindrical lamp which will be used. The drawing shows a wiring tube which is less than a third the diameter of the cylindrical lamp.

35 40 By keeping the diameter of the tube small as compared to the diameter of the cylindrical lamp and by mounting this tube parallel to the axis of this lamp and as close thereto as possible, the tube will be concealed by the lamp throughout a wide observation angle from the front of the fixture. The proportions or spacings of parts in the drawings are not necessarily correct or the best possible because of exaggeration which is desirable for clear illustration and because the form of fixture shown utilizes many present standard parts.

45 At the top of the wiring tube 5 I provide an offset arm 6, shown here as secured to the wiring tube by a plate 7 welded or otherwise per- 50 manently joined to the tube, and a machine screw

8 extending through a portion of the offset arm and threaded into an appropriate opening in the plate 7.

For supporting the flame-simulating lamp 9 at the top end of the fixture, I provide a candelabra lamp socket 10 which is aligned with the socket in the base and with the top of the cylindrical lamp. This gives the proper position for the illusion that the "flame" is issuing from the top of the "candle."

For covering and concealing the socket for the "flame" lamp and a portion of the top end of the "candle" lamp, I have shown a decorative housing or cover 11 which has a central top opening 12 therein above the socket 10. This cover is made preferably of insulating material, generally cylindrical in form, and may be contoured and colored on its outer surfaces to simulate drippings from the "candle." When an upper socket for the cylindrical lamp is required, this decorative housing also conceals this socket as well as the top end of the lamp proper. The cover is preferably made to be easily removable in an upward or forward direction from the offset end of the wiring tube after the "flame" lamp has been removed from its socket. For this purpose the rear side of the decorative candle-drip simulating cover is cut away as at 13 to allow it to be slipped either upwardly or forwardly from the offset portion. When the lamps are in place on the fixture, the top end of the cylindrical lamp and the base of the "flame" lamp will hold this cover in proper position.

Thus far I have described only the mechanical structures for supporting the lamps and for concealing unattractive parts. The electrical parts and the wiring will depend upon the types of lamps used in the fixture, and I have chosen to show a fluorescent type lamp for the "candle" and a small flame-shaped incandescent lamp for the "flame." I prefer a fluorescent lamp at the place mentioned because of the even and soft type of illumination which it produces, and an incandescent lamp where indicated because of its brightness. However, other kinds of lamps might be used as a "candle" and a neon glow type lamp might be used for the "flame" to produce a different decorative effect. I will describe the wiring and other electrical parts as if a fluorescent lamp and an incandescent lamp were used.

In the hollow portion 2 of the base I mount a switch 14 having a handle or button 15 which extends outwardly to the front of the base. A ballast 16 for the fluorescent lamp is also secured under the base in the hollow portion in any desired fashion, as by screws 17. Also secured and concealed within the hollow of the base is a terminal block 18 carrying the usual fluorescent lamp starter 19, the block being suitably secured as by screws 20 (only one shown).

The wiring for this arrangement is indicated in the diagram of Fig. 5 in which 21 represents the electrical power leads coming from a suitable source into the base, one of these lines being controlled by the switch 14 and the other passing directly from the hollow base upwardly through the tube 5 to other electrical parts. The side of the line controlled by the switch 14 has a wire 22 connected from the switch to the ballast and a wire 23 passing from the switch through the wiring tube to other electrical parts. After passing through the ballast, this portion of the circuit is connected by a wire through a hole in the base to a lamp socket contact 24 of conventional design in the lamp socket 3 which is in the top

of the supporting base. The other contact 25 in this socket is connected by a wire through a hole in the base to the starter 19 and the starter 19 is in turn connected to a wire 26 passing upwardly through the tube to other electrical parts.

When an upper socket is required for the cylindrical lamp, as in the form shown, this upper socket naturally faces the lower socket in the base. This upper socket is aligned with the "flame" socket and is preferably carried on the opposite side of the offset arm 6, facing downwardly in a direction opposite that of the "flame" socket.

The upper "candle" socket is provided with contacts 27 and 28 of the usual character for fluorescent lamps, the terminal 27 being suitably connected to the upper end of wire 26 and the contact 28 being likewise connected to the upper end of the wire 21 as indicated in the diagram. 15 When the lamp is properly placed in the upper and lower sockets these socket contacts electrically and mechanically engage with the usual terminals 29 on the top and bottom of lamp 4. Only one of these terminals is shown.

25 The wires 21 and 23 at their upper ends are also suitably connected to the inner bottom and outerside contacts of the customary style of "flame" lamp socket 10 in a manner easily understood. These contacts engage the bottom terminal 30 and the screw-threaded ferrule 31 of standard design on the lamp 9. The tube 5 at its upper end may be formed to enclose the top ends of the wires 21, 23 and 26 or these wires may be covered by an insulating tube 32 carried by the offset arm 6, as shown in the drawing.

30 It will be noted that all of the wires and other necessary electrical parts aside from the lamp sockets are housed and concealed within the base 1 and the wiring tube 5. The tube conceals the wires leading to the top end of the cylindrical lamp, the lamp itself partly conceals the tube, and the decorative cover 11 conceals the socket 10, the top end of the lamp 4, and the upper socket for the cylindrical lamp when this is used. 35 The heavier parts of the assembly can be located mostly in the base and the base may be provided with additional weight to make the entire fixture stable.

35 As will be evident from the foregoing description, certain aspects of my invention are not limited to the particular details of construction of the example illustrated, and I contemplate that various and other modifications and applications of the invention will occur to those skilled in the art. It is therefore my invention that the appended claims shall cover such modifications and applications as do not depart from the true spirit and scope of my invention.

40 What I claim as new and desire to secure by Letters Patent of the United States is:

45 1. A decorative lighting fixture of the type holding a cylindrical candle-simulating lamp of a given diameter, and a separate flame-simulating lamp at an end of the cylindrical lamp, said fixture comprising a supporting base, a first lamp socket on said base for one end of said cylindrical lamp, a wiring tube secured at one end to and extending from said base close to and parallel with the axis of said cylindrical lamp and of substantially less external diameter than said given diameter of the lamp, a second lamp socket for the other end of said cylindrical lamp carried by the other end of said wiring tube, a third socket 50 for the flame-simulating lamp carried by said tube, aligned with but oppositely facing from said

second socket, a candle-drip simulating cover surrounding said second and third sockets, and electrical connection wires in said base and tube leading to said sockets, whereby the base and the tube conceal the wires, the cylindrical lamp conceals the wiring tube, and the cover conceals the second and third sockets, to give the effect of an internally illuminated candle with flame issuing from one end.

2. A lighting fixture for supporting and illuminating a cylindrical fluorescent lamp with the terminals at either end thereof and another lamp with terminals positioned close to one end of said fluorescent lamp, said fixture comprising a supporting base having a recess therein, a lamp socket in said base adapted to receive the terminals on one end of said fluorescent lamp, a starter and ballast for said lamp mounted and concealed within said recess by said base, a wiring tube interiorly communicating with said recess and extending outwardly from the base close to said socket in a direction alongside said fluorescent lamp, an offset end of said tube, a second lamp socket on said offset end facing said first mentioned socket and adapted to receive the terminals on the other end of said fluorescent lamp, a third lamp socket mounted on said offset end

adapted to receive the terminals of said other lamp and located in alignment with but facing away from said second socket, a decorative cover on said offset end surrounding and concealing said second and third sockets and a portion of the adjoining end of said fluorescent lamp, power supply connections to said recess in the base and electrical connection wires in said recess and wiring tube leading from said power connections between said starter, ballast and sockets for energizing said lamps.
